UNITED STATES PATENT OFFICE.

GEORGE L. COLBORN, OF NEW YORK, N. Y., ASSIGNOR OF ONE-HALF TO WILLIAM GILBERT, OF NEW YORK, N. Y.

CHANGE-DELIVERING MACHINE.

1,273,742.

Specification of Letters Patent. Patented July 23, 1918.

Application filed July 12, 1917. Serial No. 180,109.

To all whom it may concern:

Be it known that I, GEORGE L. COLBORN, a citizen of the United States, and resident of the city of New York, borough of the Bronx, county of Bronx, and State of New York, have invented a new and Improved Change-Delivering Machine, of which the following is a full, clear, and exact description.

10 This invention relates to coin handling devices and has particular reference to means for delivering predetermined amounts of coins for the making of change.

Among the objects of the invention therefore is to provide a machine having a series of selective keys or plungers each bearing a number representing the amount of change that will be delivered when such key or plunger is operated.

20 A further object of the invention is the provision of a change handling device having a series of selective plungers and a master plunger or bar adapted to be locked and when so locked will prevent the manipulation of any of the coin delivery plungers.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a plan view of one adaptation of the invention designed to deliver denominations of change including all standard 40 coins, a portion of this figure being broken away to disclose a part of the interior of the mechanism.

Fig. 2 is a front elevation of the device shown in Fig. 1.

45 Fig. 3 is a vertical longitudinal sectional detail on the line 3—3 of Fig. 1.

Fig. 4 is a plan view of the lower portion of my invention with a slightly different adaptation from that of Fig. 1.

Fig. 5 is a vertical longitudinal section on the line 5—5 of Fig. 1.

Figs. 6 and 7 are vertical transverse sections on the corresponding lines of Fig. 4.

Fig. 8 is a vertical longitudinal section on the line 8—8 of Fig. 1.

Fig. 9 is a bottom plan view of the upper portion of the device corresponding to Fig. 4; and

Fig. 10 is a transverse sectional detail on the line 10—10 of Fig. 8.

Referring now more particularly to the drawings I show my device in the nature of a cabinet or casing having a base 11 having side panels 12 with provision for one or more drawers 13 for bills or the like and a rear wall 14.

At 16 I indicate a horizontal partition or deck constituting a closure for the base portion of the device and also a support for certain operating parts soon to be enumerated. 70 This deck is fixed permanently and firmly in position and at the rear end it supports a shelf 17.

Supported upon or above the shelf 17 in any suitable manner are a series of magazines 75 18, 19, 21, 22 and 23 adapted to contain a supply of standard coins of 10, 25, 5, 50 and 10 cent denominations respectively. These magazines are shown in the form of cylindrical tubes arranged with their front faces 80 in the same vertical plane, but being of different diameters according to the several different sizes of coins to be held therein, the rear portions thereof projecting rearwardly to different distances from said 85 plane. In other words all of the magazines extend to about the same distance forwardly across the upper portion of the shelf 17.

Associated with the several magazines are as many ejectors 24, 26, 27, 28 and 29 respectively, the rear ends of which lie normally just below the lower ends of the front portions of the several magazines. See Fig. 5. The plate 31 extends across the deck portion of the machine beneath the 90 magazines and with its front edge projecting slightly below the rear ends of the ejectors, the primary function of this plate be-

ing to support the supply of coins in the several magazines as indicated at 32. The plate 31 is placed below the lower end of each magazine slightly more than the thickness of a coin in said magazine and the thickness of each ejector is preferably a trifle thinner than the coin.

The several ejectors have secured thereto shanks 33, 34, 36, 37 and 38 respectively 10 and to the several shanks are secured a series of crossheads indicated at 39, 41, 42, 43 and 44 respectively. These crossheads lie in transverse vertical planes perpendicular to the axes of the several shanks. The cross- 15 heads 39 and 44 are shown as occupying the same plane while all of the other crossheads lie in different planes. A series of springs 46, 47, 48, 49 and 51 act upon the respective shanks and tend to hold the ejector plates 20 in normal idle position, the front ends of the springs all being secured to a crossbar 52 extending across the front part of the device above the deck 16.

When any ejector is forced rearward from 25 its normal position it engages the lowermost coin 32 of the stack of coins and delivers it from the lower end of the magazine so that it will drop from the plate 31 into any suitable receptacle provided for this purpose, 30 the same being indicated in this instance as a pocket 53 lined with felt 54, or its equivalent, in position to be picked up by the party receiving the change at the back end of the machine. Connected to each of the ejector 35 plates is a finger 56, the same being provided at its outer end with a shoe 57 which serves two purposes; first, the space between the outer end of the ejector and the inner wall of the shoe is large enough to permit 40 the lowermost coin of the supply to drop freely upon the plate 31 and when the ejector is operated to eject a coin, no matter how rapidly such action takes place, the shoe will prevent the coin from being tossed beyond 45 the pocket 53. In other words when the ejector is forced rearwardly to eject a coin it can only go a predetermined distance so that the shoe carried by the outer end of the finger constitutes a baffle limiting the out- 50 ward movement of the coin and insuring that the coin will drop promptly upon the cushion 54 or bottom of the pocket. In this connection it is to be noted that the finger is arranged in each instance at one side of 55 the center of the magazine so that it will not obstruct the downward delivery of the coin, when the center of the coin passes the outer edge of the plate 31. The second important office of the shoe 57 is to prevent a 60 coin from being partially delivered where it might otherwise stick and interfere with the subsequent delivery of either the same coin or the next one above it, that is to say, if the coin were to be delivered only say two 65 thirds of the distance the coins above it

would fall at their inner edges toward the plate 31. The next coin then to the one under consideration would be in position to be engaged by the ejector at its inner edge while the upper edge thereof would project 70 above the bottom end of the magazine so that the succeeding operation of the ejector would be blocked and no coin would be delivered. In the practical operation of this device, however, if a coin should be only 75 partially delivered the return of the ejector to its normal position would cause the return of the coin by reason of the shoe practically to its original position so that a subsequent action of the ejector will deliver the coin. 80 I preferably provide for the rear face of the series of magazines a shield or guard 58 which screens the magazines from the rear and serves to reduce the possibility of the coin receptacle being tampered with by a 85 stranger. The front faces of the magazines may be provided with slots 59 or other means whereby the amount of money contained therein may be indicated to the cashier at any time and whose duty it shall be to maintain a sufficient supply of coins in the different magazines for the purpose of the device.

Any suitable means may be provided to manipulate the several ejectors so as to deliver the full amount of change in a single 90 simple operation. For this purpose and with reference particularly to the five magazines indicated above for the delivery of change in even nickels I provide a plurality 100 of plungers indicated as arranged in two horizontal rows with ten plungers in each row and marked on their faces to indicate the amounts of change to be severally delivered by them, from five cents to one 105 dollar. Without unnecessarily limiting the specific arrangement of these plungers I find that the preferable arrangement is for the upper row of plungers to indicate odd 110 multiples of five cents, while the lower row of plungers indicate even multiples of five cents. The lower series or row of plungers are indicated from left to right as viewed 115 by the operator at 61, 62, 63, 64, 66, 67, 68, 69, 71 and 72, and these plungers are guided through the front panel 73 of the casing and front and rear guides 74 and 76 supported upon the deck 16. These plungers are arranged parallel to one another and to the longitudinal center of the device and 120 are adapted to be reciprocated individually without disturbing any of the others. To the rear end of each plunger is secured a shoe 77 having at least one straight side co-operating with the adjacent supporting member to prevent rotation of the plunger. See Fig. 10.

The upper series of plungers pertaining to the odd multiples of the nickel are guided in parallel relation to one another in guide 130

members 78 and 79 secured beneath the upper portion or lid 81 of the casing. These plungers are also provided with shoes 77 or other equivalent means to prevent accidental rotation thereof. At 82 I show an auxiliary shank to which is rigidly secured a crosshead 83 arranged just back of the crossbar 52. This shank 82 lies in the same plane as the lower series of plungers and is indicated as lying between the plungers 66 and 67. Toward the rear end of the auxiliary shank is a crosshead 84 which is adapted to engage either or both of the crossheads 39 and 44. The shank 82 is guided adjacent to its front end in a guide 86 secured to the deck 16 and at its rear end in one of the guide bars 76. The rotation of the shank 82 is prevented by the fact that the crosshead 83 engages the front ends of all of the lower series of plungers. See Fig. 6. Each plunger of both the upper and lower series is provided with one or more lugs, or their equivalent, for direct co-operation with one or more of the crossheads 25 through which by the manipulation of a single plunger all of the ejectors will be actuated simultaneously for the delivery of the amount of change indicated upon the front end of such plunger. I will now specifically set forth the operation of each of the plungers indicating how the delivery of the change for the same is effected. It is to be noted that this part of the description pertains particularly to the delivery of amounts 30 of change in multiples of nickels from 5 cents to one dollar, thus providing a machine adapted especially for moving picture shows, restaurants, lunch rooms and like places where change is required to be delivered accurately, rapidly and without reference to pennies.

For the delivery of a nickel the ejector 27 alone is operated and for this purpose the first plunger at the left of the upper series 45 and indicated at 87 and having a lug 88 is pushed. This lug engages the crosshead 42 connected to the shank 36 of said ejector 27. When the plunger 87 is released the spring 48 returns the ejector and the plunger to their normal position. For the delivery of ten cents the plunger 61 is operated and which through its lug 89 engages the crosshead 39 and the ejector plate 24, the single dime being delivered from the left magazine 50 18. The shank 33 and the ejector 24 are returned to their normal position by the spring 46. To deliver fifteen cents the plunger 91 is pushed. This plunger has two lugs 92 and 93 acting respectively upon the 55 crossheads 42 and 39 whereby the ejectors 27 and 24 will be actuated simultaneously. For the delivery of two dimes the plunger 62 is operated. This plunger has only one lug 94 which bears upon the crosshead 83 connected to the auxiliary shank 82 which

through its crosshead 84 actuates both crossheads 39 and 44 whereby the two ejectors 24 and 29 are operated simultaneously. For twenty-five cents the plunger 96 having a single lug 97 is operated which bears against the upper portion of the crosshead 41 connected to the shank 34 of the ejector 26. This ejector is returned to normal position by the spring 47. For thirty cents the plunger 63, through its lugs 98 and 99, actuates both crossheads 42 and 41 and the ejectors 27 and 26. For thirty-five cents the plunger 101 having lugs 102 and 103 acts upon the crossheads 41 and 39 respectively for the delivery of a quarter and a dime through the shanks 34 and 33. For forty cents the plunger 64 through its lugs 104, 105 and 106 acting respectively upon the crossheads 42, 41 and 39 will deliver simultaneously a nickel, a quarter and a dime respectively. For forty-five cents the plunger 107 is provided with a lug 108 which acts for two dimes in the same manner as the lug 94 on the shank 62 and has also a lug 109 acting for the delivery of a quarter in the same manner as the lug 97 on the plunger 96. For a fifty cent piece the plunger 66 is provided with a single lug 110 acting directly upon the crosshead 43, shank 37 and ejector 28. This ejector is returned to normal position by the spring 49. For fifty-five cents a plunger 111 is provided with lugs 112 and 113 acting similarly to lug 88 on plunger 87 and lug 110 on plunger 66 respectively. For sixty cents I eject a half dollar by means of a lug 114 on plunger 67, and a dime by means of a lug 115 acting upon the crosshead 44 of the plunger 38, this dime being delivered from the right magazine 23. Sixty-five cents is delivered by operating plunger 116 having lugs 117, 118 and 119 100 acting respectively upon the three crossheads 42, 43 and 44 whereby single coins are delivered from magazines 21, 22, and 23 simultaneously. For seventy cents the plunger 68 is provided with a lug 120 acting upon the crosshead 83 for two dimes, the same as lug 94 on plunger 62, and a lug 121 acting upon the crosshead 43. Seventy-five cents is delivered by movement of the plunger 122 having two lugs 123 and 124 acting 110 respectively upon the crossheads 41 and 43. For eighty cents I actuate the plunger 69 which has three lugs 125, 126 and 127 bearing respectively and simultaneously upon the crossheads 42, 41 and 43 thereby delivering respectively a nickel, a quarter and a half. For eighty-five cents I operate the plunger 128 having lugs 129, 130 and 131 120 operating respectively upon the crossheads 41, 43 and 44 delivering respectively a quarter, a half and a dime. For ninety cents I push the plunger 71 having four lugs 132, 133, 134 and 135 whereby I deliver simultaneously a nickel, a quarter, a half and a 130

dime. For ninety-five cents I actuate the plunger 136 having a lug 137 for two dimes, a lug 138 for a quarter, and a lug 139 for a half, these three lugs acting simultaneously upon the crossheads 83, 41 and 43. For a dollar in change I push the plunger 72 which has four lugs 140, 141, 142 and 143 serving to eject simultaneously and respectively two dimes, a nickel, a quarter and a half.

10 In order to prevent the actuation of any of these plungers and crossheads I provide a locking bar 144 guided in the upper portion of the device or in the same plane as the upper series of plungers in guides 145 and 146 having a series of lugs 147, 148, 149, 150, and 151 adapted to bear against the rear faces of the several crossheads respectively when a suitable padlock 152 or its equivalent is applied to hold the locking bar 20 from rearward movement. See Fig. 8. When unlocked, however, the actuation of any one of the crossheads 83, 42, 41, 43 or 39 will serve to move the locking bar rearwardly to its idle position where it will remain until it is drawn forward for locking purposes. The locking bar it will be noted does not act directly upon either of the crossheads 44 or 84, but these crossheads are never used independently of other cross-

25 heads which are adapted to be locked.

The drawer 13 for bills or the like is adapted to be held closed by means of a dog 153 pivoted to the rear portion of the deck 16 and adapted to be released by means of 35 a plunger 154 and when so released a spring 155 acts to start the drawer open. A spring 156 tends to hold the dog in locking position. (See Fig. 4.)

I now call attention to the means for delivering either one, two, three or four pennies by the actuation of a single plunger respectively. The attachment for this purpose is indicated in Figs. 1, 2 and 3 in connection with the usual change delivering devices, 45 and comprises a series of plungers 157, 158, 159 and 160 for the delivery of either one, two, three or four pennies respectively. The supply of pennies is kept in four magazines 161, 162, 163 and 164 shown as arranged in 50 the same vertical plane as the other coin magazines and adapted to deliver in the same pocket 53. The ejectors for these several magazines are of the same character as already described, but the relation of the 55 several plungers to one another is slightly different from those above described in connection with the main part of the machine. Each plunger of the penny device is connected directly to its own ejector plate. For 60 the delivery of a single penny the plunger 157 is actuated, the spring 165 acting to hold the same in normal idle position, one end of the spring being anchored to the crossbar 52 while the other end of the spring is connected to a collar 166. For the delivery of

two pennies the plunger 158 is pushed. This plunger carries a crosshead 167 which bears against the front face of the collar 166 whereby a penny is delivered from each of the magazines 161 and 162. Likewise the 70 crosshead 168 is secured to the third plunger 159, the free end of the crosshead acting against the crosshead 167 and finally a crosshead 169 fixed to the fourth plunger 160 acts in succession upon each of the preceding 75 plungers, effecting the delivery of a penny from each of the four penny magazines. The spring 165, through the crossheads, acts to return any or all of these plungers to normal position.

For each shank or plunger 157, 158, 159 and 160 I provide an aligned auxiliary plunger 157', 158', 159' or 160'. The abutting ends of these shanks and plungers are housed in a sleeve 170, as shown best in Fig. 85 3. This arrangement provides that when the ejector or shank is operated by or from another shank the plunger not being connected to such shank will not be disturbed, but the finger piece or plunger for the operating shank in each case will be returned to its normal position by virtue of the spring 165.

I claim:

1. In a change delivering machine, the 95 combination of a series of coin magazines, each for holding a supply of coins of a specific denomination, a slidable ejector for each magazine, a plate extending below all of the magazines, each ejector operating over said 100 plate, a rigid finger connected to and slideable with each ejector and operating below said plate and a baffle shoe carried by the outer end of the finger and adapted to coöperate with the outer edge of the coin being 105 delivered to return such coin to normal position at the bottom of the magazine in the event of failure to deliver the same, and means to actuate simultaneously as many 110 different ejectors as will yield the amount of change desired.

2. In a change delivering machine, the combination of a series of magazines each for holding a supply of coins of a certain denomination, an ejector coöperating with 115 each magazine for delivering the lowermost coin therefrom, an imperforate plate extending beneath all of the magazines and serving to support the several supplies of coins therein, the ejectors being movable across 120 the top of the plate during the delivering action, means connected to each ejector and extending thence beneath the plate and at the rear of the same and coöperating with the outer edge of a coin being delivered and 125 serving to prevent a coin from sticking in a partially delivered position, and means to actuate the several ejectors.

3. In a change delivering machine, the combination of a series of magazines each 130

for holding a supply of coins of a certain denomination, an imperforate plate extending along beneath all of said magazines and supporting directly upon its upper surface the coins in the magazines, an ejector for each magazine comprising a flat member adapted to reciprocate across the upper surface of said plate to deliver the lowermost coin from the adjacent magazine, a rigid finger fixed rigidly to the ejector and adapted to be reciprocated therewith, the finger lying and movable below said plate and at one side of the axis of the magazine, a baffle shoe secured rigidly to the outer end of the finger, said shoe coöperating with the outer edge of the coin, and means to automatically return the ejector and parts connected thereto back to normal position after actuation, said shoe serving to return the coin to its normal position in the event of failure to completely deliver it.

GEORGE L. COLBORN.

Copies of this patent may be obtained for five cents each, by addressing the "Commissioner of Patents, Washington, D. C."
